VALVE ACTUATING CAP FOR A PRESSURIZED CONTAINER

Robert Henry Abplanalp, Bronxville, and Joseph Charles Pizzurro, Scarsdale, N.Y., assignors to Precision Valve Corporation, Yonkers, N.Y., a corporation of New York

Filed May 31, 1962, Ser. No. 70,360

Term of patent 14 years

(Cl. D58—26)

FIGURE 1 is a top plan view of a valve actuating cap for a pressurized container showing our new design;

FIGURE 2 is a side elevational view;

FIGURE 3 is a front elevational view; and

FIGURE 4 is a bottom plan view thereof.

We claim:

The ornamental design for a valve actuating cap for a pressurized container, as shown.
